(57) **CLAIM**

The ornamental design for a cart control panel as shown and described.

DESCRIPTION

FIG. 1 is a top-front-left perspective view of a cart control panel according to the claimed design.

FIG. 2 is a top-front-left perspective view of the cart control panel with the light feature in an illuminated configuration.

FIG. 3 is a front view of the cart control panel.

FIG. 4 is a front view of the cart control panel with the light feature in the illuminated configuration.

FIG. 5 is a rear view of the cart control panel.

FIG. 6 is a left side view of the cart control panel.

FIG. 7 is a left side view of the cart control panel with the light feature in the illuminated configuration.

FIG. 8 is a right side view of the cart control panel.

FIG. 9 is a right side view of the cart control panel with the light feature in the illuminated configuration.

FIG. 10 is a top view of the cart control panel.

FIG. 11 is a top view of the cart control panel with the light feature in the illuminated configuration; and,

FIG. 12 is a bottom view of the cart control panel.

The dash-dash broken lines in the drawings illustrate environmental matter and portions of the cart control panel that form no part of the claimed design.

The dash-dot-dot broken lines in FIGS. 2, 4, 7, 9, and 11 of the drawings represent illumination from the light feature along the front edge of the cart control panel. The illumination is claimed, although no particular color of the illumination is claimed.

1 Claim, 12 Drawing Sheets
